UNITED STATES PATENT OFFICE.

WILLIAM G. KENDALL, OF NEWARK, NEW JERSEY.

HINGE FOR VANITY CASES.

Application filed December 13, 1922. Serial No. 606,659.

To all whom it may concern:

Be it known that I, WILLIAM G. KENDALL, a citizen of the United States, and a resident of Newark, in the county of Essex and State 5 of New Jersey, have invented a new and Improved Hinge for Vanity Cases, of which the following is a full, clear, and exact description.

The present invention relates to new and 10 useful improvements in vanity cases, and it pertains more particularly to a hinge structure therefor.

It is one of the objects of the present invention to provide a hinge structure by 15 means of which two covers may be hingedly secured to a receptacle by the same hinge member.

It is a further object of the invention to construct the hinge so that it will be sufficiently strong to perform its function, and, 20 at the same time, will have a neat appearance.

With the above and other objects in view, reference is had to the accompanying drawings, in which—

Figure 1 is a view in rear elevation of a vanity box constructed in accordance with the present invention;

Fig. 2 is a detail sectional view taken on 30 the line 2—2 of Fig. 1;

Fig. 3 is a detail view partly in elevation and partly in section, showing the receptacle body with one of the covers in open position;

Fig. 4 is a detail sectional view similar to 35 Fig. 2, showing one of the covers in open position and taken on the line 4—4 of Fig. 3;

Fig. 5 is a detail horizontal sectional view.

Referring to the drawings, the reference character 6 designates the receptacle, and 7 40 designates the two covers thereof. Each of these covers is formed with a bead 8 defining its edge. The reference character 9 designates a hinge plate, and said hinge plate is provided with tongues 10 formed on the 45 side edges of the hinge plate and adapted to project through openings formed in the body and bent inwardly of the body 6, as designated by the reference character 11 in Fig. 3. These tongues 11 provide the means 50 for securing the plate 9 to the body portion without necessitating the use of other materials, such as solder or the like.

The plate 9 has on each of its ends a

tongue 12, and said tongue is adapted to be bent about a wire 13 carried by the covers 7, 55 as indicated by the reference character 14 in Fig. 2. These wires 13 are of relatively short length and are adapted to be retained within the bead 8 of their respective covers 7, and in order to more securely hold these 60 wires 13 in place, the flange of each cover is cut out as indicated by the reference character 17, to provide tongues 18 adapted to be bent downwardly around their respective wires to secure the same against accidental 65 displacement. By this construction, it is apparent that the plate 9 with its end tongues 12 provides means for hingedly securing two covers to a single receptacle. Furthermore, 70 by providing the tongues 10 on the plate 9, the plate may be secured in position without soldering or other operation.

By providing the members 18 cut from the flanges of the cover 7, it is apparent that the wires 13 are retained against accidental 75 displacement with relation to their respective covers and that the entire structure provides a rigid hinge for the purpose.

What is claimed is:

1. A device of the character described 80 comprising a receptacle, a plurality of covers therefor, each of said covers being formed with a bead and a flange, a plate carried by the receptacle and having a tongue on each of its ends, and a wire carried by 85 the bead on each of said covers and adapted for engagement with its respective tongue of said plate to pivotally secure the covers to the receptacle.

2. A device of the character described 90 comprising a receptacle, a plurality of covers therefor, said covers each having a flange and a bead, a plate carried by the receptacle, a tongue formed on each end of said plate, a pintle carried in the bead of 95 each cover, tongues cut from the flange of each cover and adapted to secure the pintle in position therein in such a manner that the tongue at each end of the plate may be bent around its respective pintle to pivotally secure the covers to the receptacle, and tongues carried by said plate and passing through the side walls of the receptacle to secure the plate in position thereon.

WILLIAM G. KENDALL.
